UNITED STATES PATENT OFFICE.

JOSEPH A. RAYDER, OF PHILADELPHIA, PENNSYLVANIA.

ATOMIZER.

Application filed November 29, 1921. Serial No. 518,643.

To all whom it may concern:

Be it known that I, JOSEPH A. RAYDER, a citizen of the United States, residing at Philadelphia, in the county of Philadelphia and State of Pennsylvania, have invented new and useful Improvements in an Atomizer, of which the following is a specification.

This invention relates to atomizers and it has more particular reference to that type or form of such devices which are used by undertakers for spraying embalming fluids and it has for its main object to provide an atomizer characterized by its novel construction as well as its ready adaptability for treating surfaces or local positions with equal facility.

Another object of this invention is to provide an atomizer which is sanitary in all respects as well as being of simple and durable construction.

With these and other objects in view this invention consists essentially in the novel features of construction, combination, and arrangement of parts hereafter fully described and particularly defined by the appended claims.

In the further disclosure of the invention reference is to be had to the accompanying sheet of drawings constituting a part of this specification and in which like characters of reference designate corresponding parts in both the views.

Figure 1 is a top plan view of one practical embodiment of my invention; and,

Figure 2 is a central vertical section through the same.

According to my invention I construct or make from appropriate material such as glass, porcelain, light metal or the like, what may be conveniently termed an inverted cellular funnel-shaped container 3 which includes inner and outer integrally connected walls 4, 5 respectively, thus providing a container 6 for the embalming or other fluid 7. The outer wall 5 is slightly constricted to provide a neck 8 which is externally screw-threaded to receive the correspondingly threaded annular flange 9 of an air chamber 10 that is provided with a tubular neck 11 at one side which is closable by means of a screw cap 12—as shown—or to receive a sprayer nozzle as later on explained.

Diametrically opposed to the tubular neck 11 on the air chamber is an internally threaded annular flange 13 into which is se-

cured the cylinder 14, a tight joint between said parts being ensured by means of a gasket 15. This cylinder 14 is fitted with a plunger 16 of appropriate construction that is actuatable by means of a grip or handle 17 and said cylinder serves to force air into the atomizer for spraying the embalming fluid, the outer end of said cylinder 14 being closed by an appropriate removable cover 18 as will be clearly understood by those acquainted with the art to which this invention appertains.

The aforesaid inner wall 4 terminates in a tubular neck 19 that is internally screw-threaded to receive the correspondingly threaded tubular portion 20 that is concentric with the hereinbefore referred to annular flange 9 in the air chamber, and it is to be noted that this tubular portion 20 is of a length to project into the cellular funnel 3 where it is closed by means of a screw cap having a concavo-convex end 21 centrally apertured at 22; or said cap end may be provided with a nest of pin holes as will be obvious. Washers or gaskets 23, 24 respectively ensure tight joints between the parts 8, 19 and the inner underface of the air chamber 10 and thereby prevent leakage.

Holes 25 in the under part of the air chamber 10 provide for communication from said chamber with the interior of the container 6 whilst tubes 26, 27 serve as conduits for the embalming fluid therefrom to the tubular portion and neck 19 and 11 respectively.

In use it will be apparent that with the parts assembled as shown that the manipulation of the grip or handle 17 will cause air under pressure to be forced into the container 6 from the air chamber 10 which will result in the embalming fluid 7 being forced through the tube 26 into the cavity 28 of the screw cap 21 from which it will be forced under increased pressure through the hole 100 or aperture 22 in a thoroughly atomized condition, whilst the inner wall 4 of the funnel 3 will direct it on to the part being treated. When it is desired to use the neck 11 the cap 12 will be removed and replaced by the cap 21, whilst said cap 12 will close the tubular portion 20. In this case the tube 27 will direct the embalming fluid 7 into the cap 21 for local or internal treatments. It is to be observed that the outer ends of the tubes 26, 27 will be substantially closed when the cap 12 is applied thereover whereby little or no

fluid 7 will issue therefrom into the air chamber 10 but in the event of any such emission taking place it will be apparent that it will be forced back into the container 6 through the holes 25.

From the foregoing it will be clearly seen that by my invention there is provided a very effective and serviceable atomizer for the purposes specified and the right is hereby reserved to make such changes or variations therein as fairly lie within the scope of the appended claims.

Having described my invention, what I claim as new and desire to secure by Letters Patent is:

1. An atomizer comprising a cellular funnel shaped container having spaced inner and outer walls, said inner and outer walls terminating in concentric neck portions, a removable air chamber secured on said neck portions and having tubular outlets therefrom one of which is axially directed into the space inclosed by the inner wall of the container and the other away from said container, interchangeable caps for the free ends of the tubular outlets one of which is fash-

ioned concavo-convex to serve as an atomizing outlet whilst the other is a closure cap, means for supplying air under pressure to the air chamber and container, and means for conveying the container contents to the atomizing outlet cap.

2. In an atomizer including a cellular funnel shaped container having spaced inner and outer walls, said inner and outer walls terminating in concentric neck portions, the combination of a removable air chamber adapted for connection to said concentric neck portions and having tubular outlets therefrom, one of which is axially directed into the space inclosed by the inner wall of the container and the other disposed externally at right angles to said axis, away from said container, interchangeable caps for the free ends of the tubular outlets, one of which is fashioned concavo-convex to serve as an atomizing outlet whilst the other is a closure cap, means for supplying air under pressure to the air chamber and container, and means for conveying the container contents to the atomizing outlet.

JOSEPH A. RAYDER.
